SPRING MECHANISM

Edward L. Bronstien, St. Paul, Minn.

Application May 8, 1931. Serial No. 535,925

6 Claims. (Cl. 140—3)

The present invention relates to a spring assembling mechanism, and more particularly to a device for advancing a helical spring into engagement with a plurality of coil springs for 5 making a bedspring, or mattress inner-spring construction. It is not new to secure a plurality of weight supporting springs together by means of a spiral connecting wire advanced into engagement with 10 aligned pairs of weight supporting coil springs by rotating said spiral. In fact, this method of fastening together aligned pairs of coil springs is found in a patent as old as 1889, where Bonnel and Lambing, in Patent No. 405,821, show this 15 general method of construction. Various mechanisms have been devised for advancing a spiral connecting wire into engagement with the end convolutions of a plurality of aligned pairs of supporting springs by rotating the spiral by 20 means engaging the outer periphery of the spiral. Such mechanisms, while operable, are open to certain objections with which those versed in the art are familiar, among which are the difficulty of operatively guiding the helical connecting wire 25 during its advance and the difficulty of controlling the advance of the spiral and reversing the operation of the mechanism.

An object of the present invention is to make an improved and simplified mechanism for advancing a spirally coiled wire into connecting engagement with a plurality of aligned pairs of supporting springs.

In order to attain this object, there is provided, in accordance with one feature of the invention, 35 a plurality of aligned pairs of spring supporting posts and a rotatable spindle adapted to engage the wire of which a spiral connecting spring is formed to advance said spiral into connecting engagement with a plurality of aligned pairs of 40 supporting springs mounted upon spring-supporting posts.

These and other features of the invention will be more fully brought out in the following description and accompanying drawings, wherein: 45 Figure 1 is a view in front elevation of a mechanism embodying the present invention.

Figure 2 is a view in side elevation of the front portion of the mechanism shown in Figure 1, with a drive motor and spindle removed.

50 Figure 3 is a view similar to Figure 2 with a front row of supporting posts dropped to a horizontal position.

Figure 4 is a top view of a drive mechanism in an operative position and a forward corner of the 55 supporting table with the spring supporting posts

in operative position thereon, showing the method of feeding a spirally coiled connecting wire into connecting engagement with aligned pairs of springs.

Figure 5 is an enlarged view in side elevation 60 of the forward upper corner of the mechanism with the drive mechanism removed, showing the method of manipulating the forward row of supporting posts.

Figure 6 is an enlarged sectional view on the line 6—6 of Figure 2, showing the drive mechanism in position thereon, the drive mechanism being shown in raised position in solid lines and in lowered position in dotted lines.

Figure 7 is an enlarged sectional view through 70 one of the spring supporting posts and a channel support member showing the method of locking the supporting post in adjusted position.

Figure 8 is a view in side elevation of a driving mechanism with a rotatable spindle for advancing the spiral connecting wire.

Figure 9 is a view in front elevation of the mechanism shown in Figure 8.

Figure 10 is an enlarged vertical sectional view on the line 10—10 of Figure 9.

Figure 11 is an enlarged view in side elevation of magnetically controlled brake mechanism for stopping the rotation of the spindle upon shutting off the electrical current to the driving motor.

Figure 12 is an enlarged sectional view on the line 12—12 of Figure 6.

Figure 13 is an end view of the mechanism shown in Figure 10; and

Figure 14 is an enlarged sectional view of a foot 90 controlled switch operating treadle.

Referring to the drawings in detail, a table 1 is supported upon angle iron legs 2 provided with cross bracing members 3 and 4 to rigidly support the mechanism. The top of the table is preferably covered with sheet steel to form a smooth surface upon which spring structures to be assembled thereon shall be easily slidable.

A channeled and longitudinally slotted support 6 for spring-supporting posts is securely 100 mounted across the forward edge of the table top and in horizontal alignment with the top surface of the table. This channeled support 6 is constructed of a pair of angle iron members 7 and 8, the angle iron member 8 being bolted to 105 the table, and the angle iron 7 secured to the inner angle iron 8 as by means of strips 9 bolted or riveted to the ends of the angle irons.

A bracket 10 is fixedly connected to each end of the outer angle iron 7 and to each of these

brackets is pivotally connected a second bracket 11 which is connected to a second pair of spaced angle iron members 12 and 13 connected together at their ends to form a second longitudinally slotted channeled support 14 for spring-support posts.

A plurality of spring-support posts 15 are mounted in each of the channeled, slotted members 6 and 14, the preferred construction of the support posts being best illustrated in Figure 7. The posts 15 may be of cast metal or wood and are each provided with an axially disposed hole 16 threaded to receive a bolt 17 thereon. The bolt 17 is provided with a large square head portion 18 which has a free slidable fit within the channels 6 and 14. The shank of said bolt is freely slidable in the slotted openings of the channeled members 6 and 14.

A bracket 19 is securely bolted to one of the table legs 2 and a pair of parallel links 20 and 21 are pivotally connected to the bracket 19 and to a drive mechanism support member 22. The drive mechanism support member 22 has a flat, horizontally disposed upper portion 23 to which is bolted, as by means of a bolt 27, an angle member 24.

A drive mechanism 25 is bolted to the vertically disposed portion of this angle member 24 as by means of a bolt 26. By loosening the bolts 26 and 27 the angular position of the drive mechanism may be adjusted as desired.

Pivotally connected to the lower link 20 is an operating rod 28, the lower end of which is pivotally connected to a lever 29 secured to a shaft 30 which is pivotally mounted in supports 31 and 32. Foot operating pedals 33 and 34 are securely connected to the shaft 30. By depressing the pedal 34 the outer end of the lever 29 will be raised, thereby raising the drive mechanism to the solid line position shown in Figure 6, while by depressing the pedal 33 the outer end of the lever 29 will be lowered, lowering the drive mechanism to the dotted line position of Figure 6.

A coil spring 35 is connected at its lower end to the pivot at the outer end of the lower link 20, the upper end of said spring being connected to the central portion of the upper link 21. The action of this spring 35 acts to counterbalance the weight of the drive mechanism 25 and associated parts.

Also connected to the lever 29 is a rod 36, the upper end of which is connected to a bracket 37 which is mounted at the point of pivotal connection of a pair of links 38 and 39. One of these links 39 is pivotally connected at its inner end to a leg 2 of the table, while the outer end of the outer link is pivotally connected to the outer channeled member 14. These links form a toggle joint which is operated simultaneously with the mechanism for lowering and raising the drive mechanism.

When the drive mechanism support member is raised as in Figure 2, the toggle joint formed by the links 38 and 39 will be straightened, bringing the channeled members 6 and 14 into horizontal alinement, while when the drive mechanism support member is lowered, as shown in Figure 3, the toggle joint will be broken, bringing the outer channeled member 14 at right angles to the inner channeled member 6.

The drive mechanism 25, comprises a housing 40, which is preferably of cast aluminum. In the lower portion of this housing is mounted a reversible type electric drive motor 41. Rotatably mounted in the upper portion of the housing

40 is a spindle 42 which is connected by means of a suitable gear train, not shown, to the drive motor. The gear train connecting the motor to the spindle is preferably changeable for various speeds by means of a gear changing mechanism, operable as by means of a lever 43, see Figure 1. Variable speed gear trains are well known to the art so it is felt unnecessary to needlessly extend the drawings to show this feature for which no invention is claimed. This change speed mechanism is desirable so that the speed of the machine can be adjusted to conform to the proficiency of the operator.

The end of the spindle 42 extends outwardly beyond the casing and the projecting end portion of the spindle is of small diameter to easily fit within the convolutions of the spiral connecting wire which it is intended to drive and is provided with a peripheral groove 44 near its outer end to receive the wire of the connecting spiral therein.

Mounted below the spindle 42 and in alinement with the groove 44 is a wheel 45 preferably of case hardened steel rotatably mounted on a ball bearing 46. A central post 47 of the ball bearing 46 is mounted eccentrically on a disk 48 which in turn is pivotally connected to a support member 50. This support member 50 is bolted to the housing 40 as by means of a bolt 51 and adjusting screws 52 and 53 are provided to adjust the position of the support member 50 with respect to the spindle 42. The member 48 is provided with a handle 54 fixedly secured thereto and by rotating the member 48, the wheel 45, which is mounted eccentrically thereon, may be moved toward the spindle 42 to grip the wire of the connecting spiral, or by moving the handle 54 in the opposite direction the wheel 45 may be moved away from the spindle to release the wire of the connecting spiral.

A guide table 55 for the connecting spiral is mounted on the housing 40, in a position such that the axial line thereof if extended would pass approximately through the outer end of the spindle 42. This guide tube is of a diameter to receive a connecting spiral for free slidable movement therein.

A switch 56 for controlling the operation of the reversible motor is mounted on the table 1. Any suitable two-way switch may be used, that shown in the drawings comprising a strip 57 of insulative material slidably mounted in a housing 58. An insert 59 of electrically conductive material, such as copper, is securely mounted in the slidable strip 57 and is in contact with a contact member 60 mounted in the housing to normally lie above the insert 59 and a third contact member 62 is mounted to normally lie below the insert 59. An operating rod 63 is connected to the lower end of the slidable member 57, the lower end of this rod being connected to an arm 64 connected to a foot operated treadle member 65. This treadle member is pivotally mounted on supports 66. A pair of angle brackets 67 and 68 are connected to the leg 2 of the table, being resiliently held in position by bolts 69 encircled by coil springs 70 which are held in compression between the heads of the bolts 69 and the angle members 67 and 68. Collars 71 and 72 are secured to the rod 63 below and above the members 67 and 68, respectively, being held in adjusted position by set screws 73. The collars 71 and 72 are adjusted so as to normally hold the slidale member 57 in neutral position, as shown in Figure 15.

Upon depressing the rear portion of the treadle member 65, the arm 64 will be lowered, moving the slide 57 downward and bringing the insert 59 over the contact member 62 to operate the motor 41 in one direction. Upon depressing the front portion of the treadle 65 the arm 64 will be moved upward to bring the insert 59 in contact with the contact member 61 to reverse the direction of rotation of the motor. In the neutral position the motor will remain unoperated.

It is desirable to have the spindle 42 stop rotating as soon as possible after shutting off the drive current, and to this end a magnetically controlled brake may be employed. One form of such a brake is illustrated in Figure 11.

A drum 74 or collar is securely mounted on the spindle 42. A brake shoe 75 is mounted on an armature 76 which is normally held to bring the shoe 75 into engagement with the collar 74 by means of a coil spring 76—a. An electro-magnet 77 is mounted adjacent the armature and is connected in series or parallel with the motor circuit so as to be energized by the turning on of the motor drive current and to be de-energized by the shutting off of said motor drive current. It is apparent that upon energizing the electro-magnet the armature will be drawn toward the core of said magnet, releasing the brake shoe 75, and upon de-energizing said magnet the armature will be released, whereupon the spring 76—a will force the shoe 75 into braking engagement with the collar 74. Such a brake prevents overrunning of the spiral when the current is shut off.

The operation of the mechanism is as follows: The spring-supporting posts 15 are adjusted in pairs, spaced apart a required distance and firmly secured in adjusted position by screwing the members 15 tightly onto the bolts 17 to firmly grip the angle members which form the channels 6 and 14.

The pedal 33 is depressed to lower the drive mechanism and to drop the outer channel member to the position shown in Figure 3. Coil springs 78 are then mounted, one over each of the spring-supporting posts 15. The channel members 6 and 14 are constructed so that the edges of the lower convolutions of the pairs of springs 78, supported thereon, will lie adjacent one another with the parts in this position.

A spiral connecting wire 79 is then inserted in the tube 55 and the wire of the spiral is inserted between the groove 44 in the spindle 42, and the periphery of the wheel 45. The wheel 45 is dropped by means of the handle 54 to permit inserting the wire of the spiral between the spindle 42 and the wheel 45. The handle 54 is then swung to raise the wheel 45 into gripping engagement with the wire of the spiral 79.

The drive mechanism should be adjusted by the operator, if necessary, to have the tube 55 positioned with its axial line in alignment with the adjoining portions of the lower convolutions of the springs 78. This may be readily accomplished by loosening the bolts 26 and 27, sighting through the tube 55, and adjusting the drive mechanism to the proper position, and again tightening said bolts to hold the drive mechanism in adjusted position.

By means of the foot treadle 65 the switch 56 may be operated to advance the spiral, the operator guiding the spiral, if necessary, to cause it to encircle the adjacent convolutions of the pairs of springs mounted on the posts 15. Should the spiral improperly engage any of the convolutions of the springs 78, the motor may be reversed by

tilting the treadle 65 in the opposite direction to retract the spiral a required distance.

After the lower spiral 79 is run in the entire distance to engage the adjacent convolutions of all of the pairs of springs 78, the pedal 34 is depressed to raise the drive mechanism and the channel member 14 to the position shown in Figure 2. The amount of rise of the drive mechanism is constructed to be the same as the height of the coil springs 78, so that with the parts in the raised position shown in Figure 2, the springs 78 will be axially parallel to each other and their upper convolutions will be in contact with each other. The tube 55 will also have its axis in alignment with the adjoining portions of the upper convolutions of the springs 78.

A second spiral 79 may then be inserted in the tube 55 and gripped between the spindle 42 and the wheel 45, as described above for the lower spiral. The drive motor may then be operated to rotate the spindle 42 and advance the spiral into connecting engagement with the adjoining portions of the upper convolutions of the springs 78.

The double row of springs 78, now connected by means of the spirals 79 at their upper and lower convolutions, may now be lifted bodily from the posts 15 and the row of springs 78 formerly on the forward row of posts supported on the channel 14 are moved onto the rear row of posts 15 supported on the channel 6. Additional loose springs 78 are then placed on the front row of posts 15 and the drive mechanism 25 and forward channel member 14 are dropped to the position shown in Figure 3.

Spiral connecting members are similarly advanced into connecting engagement with the adjacent portions of the lower and upper convolutions of these springs and additional rows of springs can be added by repeating the above described process until a spring assembly of a desired length is completed.

The mechanism is simple and positive in operation, the wire of the spiral is firmly gripped by the driving mechanism, and the driving of the spiral is under full control of the operator at all times. The adjustable mounting of the posts permits the springs to be spaced laterally as desired and the dropping of the front row of posts to a horizontal position, while inserting the lower spiral exposes the adjoining portions of the lower convolutions of the operator.

It was formerly necessary to insert the top spiral, then turn the entire spring assembly over so as to bring what was formerly the bottom of the spring assembly on top and then insert the other spiral on the top so as to bring it within the reach of the operator for guiding. It is necessary for the operator to be able to reach the spiral for guiding during the advance of the spiral, since in case the end of the spiral strikes the wire of one of the springs 78 the spiral may be displaced and fail to properly engage the adjoining convolutions of the springs 78.

I claim:

1. A spring assembling mechanism, comprising aligned spring positioning means, a feed device for a spiral connecting wire, said feed device comprising a guide member positioned to direct a spiral connecting wire supported therein toward said spring positioning means, a rotatable spindle adapted to be inserted interiorly of said spiral and an oppositely rotatable member mounted adjacent said spindle and adapted to grip the wire 150

of said spiral between said spindle and said rotatable member.

2. In a spring assembling mechanism, a weaving mechanism comprising a rotatable spindle adapted to have an end thereof inserted interiorly of a spiral, an oppositely rotatable member mounted adjacent said spindle and adapted to grip the wire of said spiral between said spindle and said rotatable member, and means for rotating said spindle and said rotatable member to simultaneously rotate and advance said spiral.

3. In a spring assembling mechanism, a rotatable spindle and oppositely rotatable member mounted adjacent said spindle and having its axis of rotation parallel with the axis of said spindle, said spindle and said rotatable member being relatively movable in a plane at right angles to the axes of rotation thereof to grip a strand of a helical therebetween to rotate and advance said helical upon a rotation of said spindle and said rotatable member.

4. In a spring assembling mechanism, a guide member adapted to receive a helical, a rotatable spindle mounted at an acute angle with respect to said guide means, said spindle having an end thereof adapted to enter said spiral between adjacent convolutions thereof, a rotatable member mounted with its axis of rotation substantially parallel to that of said spindle and spaced

from said spindle a distance sufficient to grip the wire of said helical between said spindle and said rotatable mechanism.

5. A mechanism for simultaneously rotating and advancing a spiral, comprising rotatable means having an end thereof adapted to be inserted within said spiral to engage an inner surface thereof, and an oppositely rotatable member mounted adjacent said first rotatable member and adapted to engage an outer surface of said spiral to grip the wire of said spiral between said rotatable members.

6. In a spring assembling mechanism, a frame, a pair of rows of aligned spring holding means carried by said frame, said rows being spaced apart to position springs supported on said spring holding means with their upper and lower convolutions laterally contiguous to each other, a spiral-rotating mechanism mounted on a side of said frame, said spiral rotating mechanism having a spindle adapted to be inserted interiorly of a spiral to be rotated thereby and an oppositely rotatable member mounted adjacent said spindle to frictionally grip a strand of said spiral to rotatably advance said spiral into securing engagement with springs mounted on said spring-holding means.
